UNITED STATES PATENT OFFICE.

CARL BOHNEN, OF ST. PAUL, MINNESOTA.

DESIGN FOR A FOB, PENDANT, OR SIMILAR ARTICLE.

53,144.

Specification for Design.

Patented Apr. 1, 1919.

Application filed August 5, 1918. Serial No. 248,481. Term of patent 7 years.

To all whom it may concern:

Be it known that I, CARL BOHNEN, a citizen of the United States, residing at 512 Holly avenue, in the city of St. Paul, in the county of Ramsey and the State of Minnesota, have invented a new, original, and ornamental Design for a Fob, Pendant, or Similar Article, of which the following is a specification, reference being had to the accompanying drawings, forming part thereof.

The drawing represents the article as a fob or pendant, which may be suspended by

suitable means engaging the ring shown at the top of the article.

Figure 1. is a front view of one of the sides of the article.

Fig. 2. is a front view of the other side thereof and

Fig. 3. is a vertical section through the center of the article.

I claim:

The ornamental design of a fob, pendant or similar article as shown.

CARL BOHNEN.
